Pierre James
ATTORNEY

UNITED STATES PATENT OFFICE.

TOM W. SAUL, OF SEATTLE, WASHINGTON.

MILK-BOTTLE-STOPPER REMOVER.

1,387,014.

Specification of Letters Patent. Patented Aug. 9, 1921.

Application filed May 11, 1921. Serial No. 463,789.

To all whom it may concern:

Be it known that I, TOM W. SAUL, a citizen of the United States, residing at Seattle, in the county of King and State of Washington, have invented certain new and useful Improvements in Milk-Bottle-Stopper Removers, of which the following is a specification.

The object of my invention is the provision of an inexpensively constructed device whereby paper stoppers may be conveniently removed from milk bottles or the like without splashing or spilling the milk.

A further object is to provide a device of this character which is engageable over the bottle so that a stopper which has been removed therefrom will be held to have the drippings therefrom fall into the bottle mouth.

Other objects and advantages of the invention will appear in the following description.

The invention consists in the implement hereinafter described and claimed.

In the accompanying drawings,—
Figure 1 is a vertical section of the upper portion of a milk bottle, the paper stopper therefor, and showing in side elevation my improved device applied to the stopper for removing the same.

Fig. 2 is a similar view with the stopper impaled on the device with the latter engaged upon the bottle. Fig. 3 is a top plan view of the device.

As illustrated in the drawings, a device embodying my invention is constructed of a single piece of wire which is formed to provide a central portion of substantially an S-shape comprising two bends or loops 5 and 6 and from which prong and shank elements 7 and 8 extend in opposite directions.

The shank element 8 is straight, or nearly so, from the bend 5 to a bend 9 and thence terminates in a laterally disposed arm 10, Fig. 3, which is arranged at right angles to the shank part 8 and is advantageously provided with a sharpened extremity 11. The prong 7 is curved as shown in Figs. 1 and 2, having a general direction parallel to the shank part 8 and is flattened and tapered to a sharp point 12.

With the exception of the arm 10 the axes of the aforesaid parts of the device are located in the same vertical plane.

The bend or loop 5 is sufficiently open to provide therein a recess 13 adapted to engage over the bottle as shown in Fig. 2. The other bend or loop 6 is desirably closed, or nearly so, in order to present the prong 7 substantially in a transverse plane extending through the center of the loop 5 and parallel to the shank part 8.

For removing a paper disk or stopper 14 from the mouth recess 15 of a bottle 16, the device is grasped by its shank and loop portions in the hand of the operator who thereupon pushes the prong into the stopper substantially as represented in Fig. 1. With the prong thus penetrating the stopper, the operator pushes downwardly upon the shank as indicated by the arrow in Fig. 1 until the device encounters the bottle at 17 which latter serves as a fulcrum for the device and the stopper is pried out of the bottle in the continued downward travel of the shank.

After the stopper has been thus removed from the bottle the milk may be poured therefrom as required; the device is hooked upon the bottle as represented in Fig. 2 to retain the stopper above the bottle mouth whereby any milk or cream dripping from the stopper will enter the bottle.

The function of the arm 10 is to serve in the hand of the operator as a support to maintain the device in a substantially vertical plane. The arm 10, it may be mentioned, also provides an instrumentality for puncturing a condensed milk can as will be understood from Fig. 3, wherein such a can is indicated by dotted lines.

What I claim, is,

1. A device of the character described comprising a piece of wire formed to provide a pointed prong at one end, a shank at the other end and with two reverse bends at about its midlength, one of said bends affording a recess which is engageable with the mouth of a bottle to maintain the device in a substantially vertical position with the prong end thereof uppermost.

2. A device of the character described comprising a piece of wire bent about midway of its length to a substantially S-shape form, said wire extending from such bent portion to provide at one side thereof a prong and at the other side a shank which terminates in an arm disposed in rectangu-

lar relation to the plane of the bent portion of the device, one of the loops of said bent portion affording a recess longitudinally of the device and between the other loop and 5 said shank.

3. A bottle-stopper removing device having a pointed end and a hook intermediate its length, said hook being adapted to en-

gage the mouth of a bottle to maintain the device in a substantially vertical position. 10
Signed at Seattle, Washington, this 6th day of May, 1921.

TOM W. SAUL.
